(57) **CLAIM**

The ornamental design for dashboard for vehicles, as shown and described.

DESCRIPTION

1. Dashboard for vehicles

1.1 : Perspective

1.2 : Front

1.3 : First side view

1.4 : Rear view

1.5 : Second side view

1.6 : Top

1.7 : Bottom

Design 1: The present design relates to a dashboard for vehicles in which Fig. 1.1 is a perspective view; Fig. 1.2 is a front view thereof; Fig. 1.3 is a first side view thereof; Fig. 1.4 is a rear view thereof; Fig. 1.5 is a second side view thereof; Fig. 1.6 is a top view thereof; and Fig. 1.7 is a bottom view; the broken lines shown are for the purpose of illustrating portions of the dashboard that form no part of the claimed design.
